NAME PLATE HOLDER

James R. Norrbohm, 9936 Columbus Ave.,
Minneapolis, Minn. 55420

Filed Jan. 2, 1973, Ser. No. 320,561

Term of patent 3½ years

Int. Cl. D20—03
U.S. Cl. D96—12 F

FIG. 1

FIG. 2

FIG. 3

FIG. 4

FIG. 5

FIG. 1 is a perspective view of a name plate holder embodying my new design;

FIG. 2 is a front view thereof;

FIG. 3 is a side view thereof;

FIG. 4 is a rear view thereof; and,

FIG. 5 is a vertical section taken substantially along line 5—5 of FIG. 2.

The name plate is shown in broken lines in FIGS. 1 and 2 for illustrative purposes only.

I claim:

The ornamental design for a name plate holder, substantially as shown and described.
